UNITIZED TABLE AND MULTIPLE CHAIR COMBINATION

Roy W. Anderson, 216 Bartley Bull Parkway,
Brampton, Ontario, Canada

Filed Dec. 3, 1968, Ser. No. 14,770

Term of patent 3½ years

Int. Cl. D6—01

U.S. Cl. D33—14

FIG 1

FIG 2

FIG 3

FIG 4

FIG 5

FIG. 1 is a perspective view of the unitized table and multiple chair combination;

FIG. 2 is a top view of the unitized table and multiple chair combination; and

FIGS. 3 and 4 are edge views of the unitized table and multiple chair combination looking along the direction of arrows 3 and 4 in FIG. 2, respectively.

FIG. 5 is an edge view of the unitized table and multiple chair combination looking generally in the direction of arrow 3 but with chairs removed and other chairs swung away from the orientation shown in the top view of FIG. 2.

I claim:

The ornamental design for a unitized table and multiple chair combination, as shown and described.
